DESIGN FOR A GIRDLE OR THE LIKE

Herman Kress, New York, N. Y.

Application May 29, 1943, Serial No. 110,327

Term of patent 3½ years

To all whom it may concern:

Be it known that I, Herman Kress, a citizen of the United States, residing at New York, in the county of New York and State of New York, have invented a new, original, and ornamental Design for a Girdle or the like, of which the following is a specification, reference being had to the accompanying drawing, forming part thereof.

Fig. 1 is a rear view of a girdle, or the like, showing my new design; and

Fig. 2 is a front view thereof.

The characteristic feature of my design resides in the combination on the girdle disclosed of the substantially V-shaped piece arranged on the back thereof, as shown.

I claim:

The ornamental design for a girdle or the like, as shown and described.

HERMAN KRESS.
